DESIGN FOR A GLASS HOLDER

Mainart H. Hewlett, Hewlett, N. Y.

Application December 26, 1933, Serial No. 50,218

Term of patent 3½ years

To all whom it may concern:

Be it known that MAINART H. HEWLETT, a citizen of the United States of America, residing at Hewlett, in the county of Nassau, Long Island, and State of New York, has invented a new, original, and ornamental Design for a Glass Holder, of which the following is a specification; reference being had to the accompanying drawing, forming part thereof.

I claim:

The ornamental design for a glass holder, as shown.

In testimony whereof I affix my signature.

MAINART H. HEWLETT.
